Primary Examiner — Zenia Bennett(74) *Attorney, Agent, or Firm* — Plumsea Law Group, LLC(57) **CLAIM**

The ornamental design for a toy figurine head, as shown and described.

DESCRIPTION

FIG. 1 is a front perspective view of a toy figurine head showing the new design;

FIG. 2 is a front elevational view of the toy figurine head of FIG. 1;

FIG. 3 is a side elevational view of the toy figurine head of FIG. 1, the opposite side elevational view being a mirror image;

FIG. 4 is a rear elevational view of the toy figurine head of FIG. 1;

FIG. 5 is a top plan view of the toy figurine head of FIG. 1; and,

FIG. 6 is a bottom plan view of the toy figurine head of FIG. 1.

The broken lines are for environmental and illustrative purposes only and are not part of the claimed design.

1 Claim, 3 Drawing Sheets(56)
